UNITED STATES PATENT OFFICE.

ANGELO ROBERT CLAS, OF TOLEDO, OHIO, ASSIGNOR TO THE TOLEDO AUTOMOTIVE PRODUCTS COMPANY, A CORPORATION OF OHIO.

WINDOW REGULATOR.

Application filed June 23, 1924. Serial No. 721,623.

To all whom it may concern:

Be it known that I, ANGELO ROBERT CLAS, a citizen of the United States, and a resident of Toledo, in the county of Lucas and State 5 of Ohio, have invented a new and useful Window Regulator, which invention is fully set forth in the following specification.

This invention relates to window regulators of the type employing a swinging window 10 control arm and intended more particularly for use in closed vehicles.

An objection to the use of regulators of this class is that the power required to raise an associated window is not uniform 15 throughout the movement of the window but gradually increases from the lowermost throw of the arm upward until it is at right angles to the line of movement of the window and then diminishes to the uppermost 20 point of the throw.

The primary object of the invention is to overcome or lessen the objection above noted by so mounting the swinging window control arms of apparatus of this class and 25 connecting them to the power means that the raising power required for the associated window is substantially uniform throughout its movements, or at least is more nearly uniform than with the types of regulators 30 of the swinging arm type heretofore used.

A further object of the invention is the provision of a window regulator of the class described, wherein the movement of the point of engagement of the control arm with 35 the window lengthwise of the engaged edge thereof is materially reduced so that the point of connection of the control arm with the window is maintained substantially central of the side edges of the window and the 40 tendency of the window to tilt and bind in its slideway when a raising pressure is applied thereto by the arm is practically eliminated.

The invention is fully described in the 45 following specification, and while in its broader aspect it is capable of embodiment in numerous forms, a few forms only thereof are illustrated in the accompanying drawings, in which,—

Figure 1 is a side elevation of a mechanism embodying the invention with the window frame, and window with which associated fragmentarily shown, and with the window partly lowered. Figure 2 is a 50 cross-section on the line 2—2 in Fig. 1. Fig. 3 is an enlarged vertical section through the control arm of the mechanism and the lower edge portion of the window at the point of engagement of one with the other. Fig. 4 is an enlarged section of a slightly 60 modified manner of slidably connecting the control arm with the actuating member therefor. Fig. 5 is a fragmentary side elevation thereof. Fig. 6 is a view similar to Fig. 1 with a slightly modified form of 65 mounting of the control arm. Fig. 7 is a section on the line 7—7 in Fig. 6. Fig. 8 is an enlarged vertical section through the control arm of the mechanism and the lower edge portion of the window at the point of 70 engagement of one with the other. Fig. 9 is a view similar to Fig. 1 with a modification of the invention, and Fig. 10 is a similar view with still another modification of 75 the invention.

Referring to the drawings, 1 designates a window or door frame in which a glass 2 or other form of window member is mounted for vertical reciprocatory movements in a slideway provided in the frame and 80 adapted, when in raised position, to close a window opening in the frame, and, when lowered, to enter a well or chamber in the lower portion of the frame, as well understood in the art. The frame 1 is provided 85 across the upper portion of the well or chamber therein at the outer side thereof with a board or member 3, usually referred to as a lock-board.

The window regulating mechanism embodying the invention employs in the different illustrated embodiments thereof a bracket plate 4, preferably stamped from sheet metal and secured to the lock-board 3 by screws or in any suitable manner at the 90 inner side thereof, and having its lower end projecting below the board. This bracket plate is located at one side of the window center and forms a journal having a main operating shaft 5, which projects through 100 the board 3 and carries a crank or other suitable operating member (not shown) at its outer end. The shaft 5 is provided at its inner end with a pinion 6 in driving mesh with the teeth of a gear 7, the pivot 105 or supporting stud 8 of which is carried by the lower end portion of the bracket plate 4, in the present instance, below the lock-board 3. The gear 7 may be of sector form, as shown in Figs. 1, 6 and 10, or of circular 110

form, as shown in Fig. 9. It is evident that rocking or rotary movements may be imparted to the gear 7 by a turning of the drive pinion 6. In each form of the invention, 5 the gear 7 acts on a swinging window control arm 9 to impart window raising and lowering movements thereto and the manner of mounting this arm and of connecting the same with the gear constitutes the present invention. 10

In Figs. 1, 2, 6, 7 and 10 the control arm 9 lies across the side of the gear 7 opposed to the bracket plate 4 and is in sliding connection with the gear to enable the arm to 15 have longitudinal sliding or reciprocatory movements across the same. The sliding connection of the arm with the gear is disposed intermediate the ends of the arm and comprises a pivot stud 12 projecting from 20 a side of the gear sector near one end thereof and through a longitudinally extending slot 13 in the arm. The stud 12 instead of projecting through a slot in the control arm may carry a yoke 14, which slidably embraces the arm, as shown in Figs. 4 and 5. 25

In Figs. 1 and 2 the inner end of the arm 9 or that opposed to the window engaging end thereof is connected to the lower end of the bracket plate 4 to the opposite side of 30 the gear pivot 8 to the window engaging end of the arm by a link 15, one end of said link being pivoted at 16 to the arm end and the other end being pivoted at 17 to the bracket plate. This provides a compensating 35 connection between the arm and gear whereby upon a swinging of the arm by movement of the gear it is caused to have longitudinal movement to maintain its free or window engaging end in substantially 40 a straight line which is parallel with the movement of the window when the arm is swung. With this manner of connection of the arm 9 with the bracket plate 4, the window engaging end of the arm has a very 45 slight movement lengthwise of the engaged edge of the window, such movement being confined substantially within the two parallel lines *a*. In this case it is preferable to provide the free end of the arm with a 50 roll 10 for engagement with the window edge and to have the roller carrying stud 11 working in a slightly elongated slot in a plate 11^a attached to the window edge.

It is evident that in the use of this mechanism a rocking of the gear 7 applies power 55 to the arm 9 through its sliding point of connection with the gear, and that the link 15 acts as a compensating fulcrum for the arm which enables the arm to have rocking movements imparted thereto from rocking movements of the gear and at the same 60 time permits the arm to move longitudinally crosswise of the actuating means a sufficient extent for its point of connection with the window to move in substantially a straight

line instead of an arc concentric to the gear axis, as is the case with the swinging arm types of regulators heretofore used.

In Figs. 6 and 7 the purpose of the compensating link 15 is performed by the fulcrum pin 18 of the arm 9, working in a cam slot 19 in the foot or angled portion of the bracket plate, the foot portion of the plate being enlarged slightly for such purpose over that of the bracket plate in Fig. 1. 75 With this form of the invention, the cam slot 19 may be so laid out that the point of engagement of the free end of the arm 9 with the window member 2 moves in a perfectly straight line parallel with the line of movement of the window, as indicated by the line *b*, and the arm may, therefore, have a stud 20 in pivotal engagement with a lip plate 21 on the lower window edge, such point of engagement being disposed centrally of the width of the window so that the window is balanced thereon and does not have a tendency to tip in one direction or the other into binding engagement with the slideway. 85 90

In Fig. 10 the compensating connection for the arm 9 comprises a pair of links 22 and 23, each of which is connected at its inner end to a pivot stud 24 in the arm 9 while the other end of the link 22, which is the shorter of the two, is pivoted at 25 to the lower end of the bracket plate 4 below the pivot stud 8 of the gear, and the opposite end of the other link 23 is pivotally connected at 26 to the adjacent end portion of the gear sector or the opposite end of said sector to the connection 12 of the arm therewith. In this embodiment the link 23 is moved by movements of the gear 7 and controls the swinging movements of the link 22 and consequently of the inner or fulcrum end of the arm 9. With this construction the movement of the window engaging end of the arm 9 lengthwise of the window edge is greater than in the form of the invention shown in Fig. 1, but is considerably less than if the arm were fixed to the gear and the swinging axis thereof that of the gear. 100 105 110

In Fig. 9 a full gear, which may be designated 7^a, is employed and the arm 9 is pivotally connected at its inner end to the gear near one edge thereof by a pivot stud 28. The arm, when in its horizontal position, extends diametrically across the gear and has its longitudinally extending slot 29 receiving a guide stud 30, which is fixed to the toe portion bracket of the angled plate 4 without the edge of the gear and in a horizontal plane with the gear axis. When the window member is in full lowered position, the arm 9 assumes the inclined dotted line position *c* with its pivot 28 disposed adjacent to the pivot stud 30 and above the same, and when the window is in its full raised position the arm assumes the dotted line 115 120 125 130

position *d* with its pivots 28 adjacent to the pivot stud 30 below the same. It is evident with this construction that when a movement of the gear 7^a is started to effect a raising of a window from its full lowered position, a longitudinal pull is first imparted to the arm 9 and then during a continuance of such pull the arm is rocked to swing its free end upward to horizontal position, the arm during substantially all of the movement of the gear to the full line position of the parts shown being moved inward to shorten the distance between the gear axis and the window engaging end of the arm. During the upward movement of the free end of the arm from the full line position shown, the arm has a combined pushing and rocking movement imparted thereto. The movement of the point of engagement of the arm with the window during a complete window raising stroke of movement of the arm travels a path substantially like that of the dotted line *e*.

It is evident with each form of the invention shown that during an operating movement of the arm the distance between the window engaging end of the arm and the gear axis, or the effective length of the arm, varies so that such length is shortest when the arm is substantially midway of its stroke of movement, or in a plane substantially at right angles to the line of movement of the engaged window, thereby lessening the force which would otherwise be required to raise the window when in substantially its midway position.

In mechanisms of this class it is common to provide a spring to counter-balance the weight of the window member, and it will, therefore, be understood that such a spring may be used in connection with any one of the different forms of the invention shown. In Figs. 2 and 7, 31 designates a spring of the helical type which has one end fixedly connected to the stud 8 and its other end connected to the bracket plate 4, whereby the turning of the gear 7 in one direction is resisted by the spring.

I wish it understood that my invention is not limited to any specific construction, arrangement or form of the parts as it is capable of numerous changes and modifications without departing from the spirit of the claims.

Having thus described my invention, what I claim as new and desire to secure by Letters Patent is:—

1. In a window regulating mechanism, a

stationary member, a rotatable actuating member, a swinging window control arm connected intermediate its ends for longitudinal sliding movements to one of said other members, and a fixed member connected to have predetermined limited compensatory movement relatively to the other member, whereby the arm is rocked by a rotation of the actuating member and is at the same time longitudinally moved to vary the distance between the free end of the arm and the axis of the actuating member. 70

2. In combination, a frame, a member 60
slidable in the frame, a bracket carried by the frame, a segmental gear rockably carried by the bracket, manual operating means for the gear, a swinging arm extending across 75
the gear and having its outer end pivotally connected to said member for movements with the member, a compensating fulcrum connection between the inner end of the arm and the bracket including a member fixed 80
to said arm which permits predetermined limited movements of the arm fulcrum with respect to the bracket, and a slidable actuating connection between the gear and arm. 85

3. In combination, a frame, a member 85
slidable therein, an actuating means carried by the frame and having a rotatable part, an arm carried by the actuating part for longitudinal movements transverse to the part axis and having one end connected to 90
said member, and a connection between the other end of said arm and the frame including a member fixed to the arm and adapted to have limited predetermined compensatory movement relatively to the frame whereby 95
said arm, when swung with the rotatable actuating part, is caused to have longitudinal movements relative thereto to vary to a predetermined extent its leverage on the 100
slidable member.

4. In a window regulating mechanism, a frame, a window slidable in the frame, a bracket carried by the frame, a toothed sector pivoted to said bracket, means for operating said sector, a swinging arm extending across said sector and having its outer end connected to said window for movement therewith, a link connecting the inner end of the arm and the bracket to permit predetermined movement of the arm with respect 110
to the bracket, and a slidable actuating connection between the sector and arm. 105

In testimony whereof I have hereunto signed my name to this specification.

ANGELO ROBERT CLAS.
